UNITED STATES PATENT OFFICE.

NELSON S. STEWART, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

47,675.

Specification for Design.

Patented Aug. 3, 1915.

Application filed June 9, 1915. Serial No. 33,218. Term of patent 3½ years.

To all whom it may concern:

Be it known that I, NELSON S. STEWART, a citizen of the United States, residing in the city of Amsterdam, in the county of Montgomery and State of New York, have invented a new, original, and ornamental Design for a Rug or Carpet Sizes, of which the following is a specification, reference being had to the accompanying drawing, forming a part thereof.

The drawing illustrates a portion of a rug, showing my new design.

I claim:

The ornamental design for a rug, substantially as shown.

NELSON S. STEWART.

Witnesses:

W. H. SEALEY,
P. S. NEWELL.
